(57) **CLAIM**

The ornamental design for a combination recycling and trash receptacle bin, as shown and described.

DESCRIPTION

FIG. 1 is an isometric view of the combination recycling and trash receptacle bin showing our new design;

FIG. 2 is a front elevational view, with the rear view being a mirror image thereof;

FIG. 3 is a right side elevational view, with the left side being a mirror image thereof;

FIG. 4 is a top plan view thereof;

FIG. 5 is a bottom plan view thereof;

FIG. 6 is an isometric right side exploded view thereof;

FIG. 7 is an isometric left side exploded view thereof;

FIG. 8 is a front elevational exploded view thereof;

FIG. 9 is a rear elevational exploded view thereof;

FIG. 10 is a left side elevational exploded view, with the right side elevational exploded view being a mirror image thereof;

FIG. 11 is a top plan exploded view thereof; and,

FIG. 12 is a bottom plan exploded view thereof.

The broken lines shown in the figures are included for the purpose of illustrating portions of the claimed design and forms no part of the claimed design.
